UNITED STATES PATENT OFFICE.

JOHN P. MENTZER, OF CHICAGO, ILLINOIS.

FUSE DEVICE.

1,405,533.

Specification of Letters Patent. Patented Feb. 7, 1922.

Application filed April 19, 1917. Serial No. 163,170.

To all whom it may concern:

Be it known that I, JOHN P. MENTZER, a citizen of the United States, residing at Chicago, in the county of Cook and State 5 of Illinois, have invented a certain new and useful Improvement in Fuse Devices, of which the following is a full, clear, concise, and exact description, reference being had to the accompanying drawings, forming a 10 part of this specification.

My invention relates to fuse devices and especially to fuse devices having one or more enclosed or embedded fuses, and to the process or method of making same.

15 One object of the invention is to provide a simple, practical and efficient construction of fuse device.

A further object of the invention is to provide a practical and economical process 20 for the manufacture of fuse devices of this kind.

A further object of the invention is to arrange for the easy manipulation of the fuse device when made with a plurality of fuses 25 so as to permit the several fuses to be brought into use one after the other.

A further object is to provide for the ready renewal of the fuse of fuses after use.

30 A still further object is to insure the satisfactory operation of each of the fuses in a plurality fuse device without interfering with the others.

Further objects of the invention will be 35 pointed out hereinafter.

In the accompanying drawing Fig. 1 is a longitudinal section of a fuse device embodying my present invention;

Fig. 2 is a plan view of the plug portion 40 of the device;

Fig. 3 is a plan view of the separable base of said plug portion.

Fig. 4 is a perspective view partly broken away of a part of said plug portion.

45 The device shown in the drawings for carrying out the invention comprises plug and socket portions 1 and 2. The plug 1 is provided with a metallic shell 3 of tubular form which is secured to the base portion

50 4 of the plug, as by having one end embedded therein (Fig. 1). This shell 3 is preferably made of metal such as brass and is screw threaded so that it can be screwed into the socket 2, the latter preferably being provided with a metallic tubular portion 5 threaded correspondingly to the shell

3. Within the shell 3 is the body portion or fuse holder 6 of the plug, said body portion or fuse holder being provided with one or more fuses, four fuses 7 being shown. 60 The number of fuses 7 may be more or less than the four shown. These fuses 7 extend preferably from end to end of the body or holder 6 and when there are a plurality they are crossed at the outer end of the 65 body or holder 6 and covered with a metallic cap piece 9 by which electrical connection is made with all of said fuses. The other ends 10 of said fuses 7 are terminated at the inner end of the body 6 so that contact 70 may be made with any one of them. The base portion 4 of the plug 1 is provided with a contact 11 (Fig. 3) which is capable of making electrical connection with one of the ends 10 of the fuses 7, namely, that 75 end portion 10 which is adjacent to and in contact therewith.

The body or holder 6 is, however, adapted to be removed from the shell 3 and replaced therein, being fitted snugly but at the same 80 time removably within the shell 3. The inner end of said body or holder 6 and the adjacent portion of the base 4 are furthermore provided with cooperating means by which the body 6 may be held against rotation, but which permit a relative rotary 85 movement when desired, so as to allow the ends 10 of the fuses 7 to be brought into contact one after the other with the contact 11. As an advantageous arrangement, the 90 base 4 is provided with recesses or sockets 12 of which there are preferably four, arranged equidistant from one another, and the holder 6 is provided with corresponding projections 13 adapted to fit into the recesses 95 12. In this way when the holder 6 is inserted within the shell 3 to such an extent that the projections 13 fit into the recesses 12, the holder 6 will be held against rotation and one of the fuse ends 10 will be maintained in contact with the contact piece 11. When, however, that fuse blows or for 100 some other reason it is desired to change fuses, the holder 6 may be moved outwardly in the shell 3 sufficiently to withdraw the 105 projections 13 from the recesses 12, whereupon the holder 6 may be turned a quarter turn and then pushed back so that the projections 13 will again enter the recesses 12, but this time with another fuse end 10 in 110 contact with the contact 11, thereby including another fuse in circuit. This operation

may be repeated until all four fuses are blown, after which a new body 6 with four fresh fuses is inserted.

The socket 2 is provided with a suitable terminal 14 having a contact such as the spring 15 by which a circuit wire may be connected with said terminal 14 and then connected in circuit with one of the fuses. The contact 11 on the base 4 is understood to 10 be connected by a suitable wire or connection (not shown) by which said contact 10 may be included in said circuit.

As a matter of further improvement, the holder 6 and preferably the base 4 are made 15 of some suitable insulating material, such for example as bakelite, which can be molded in the desired shape and size. This is particularly desirable because material of this kind can be sized very accurately, which 20 is not true of porcelain and many other kinds of insulating material. For instance the holder 6 may be very accurately the precise size to fit perfectly in the shell 3, snugly enough to prevent accidental 25 placement, but loosely enough to permit movement to change fuses or bodily removal to substitute a new holder.

In such case the fuse or fuses in the holder 6 will be embedded in the bakelite 30 or other material when the same is in a loose or powdered form and will then be compressed in a heated condition to the desired shape and size. Similarly the base 4 will be molded to the desired shape and

size with the end of the shell 3 embedded 35 in it.

It will be understood that changes and modifications may be made without departing from the spirit of the invention.

What I claim is:

A fuse device comprising plug and socket members, whereof the plug member consists of a body portion and a base provided with a tubular member into which the body portion is fitted, said body portion being provided with longitudinally extending fuses, the ends of which project from the opposite ends of the body portion, said base being provided with a contact adapted to make contact with a projecting end of a fuse, and said body portion and base being relatively rotatable and provided with interlocking devices for preventing relative rotation, said relative rotation permitting said base contact to make contact with the ends of the different fuses one after the other, and the interlocking devices being arranged to interlock said members to maintain the same in positions in which contact is made with said fuses, said socket device being provided with a threaded member adapted to receive the threaded tubular member on said base.

In witness whereof, I hereunto subscribe my name this 6th day of April, A. D., 1917.

JOHN P. MENTZER.

Witnesses:

A. L. JONES,
O. M. WERMICH.
